UNITED STATES PATENT OFFICE.

HOWARD COOPER, OF WINNIPEG, MANITOBA, CANADA.

CENTERING-FORM.

1,160,382.

Specification of Letters Patent.

Patented Nov. 16, 1915.

Application filed February 1, 1915. Serial No. 5,587.

To all whom it may concern:

Be it known that I, HOWARD COOPER, a citizen of the Dominion of Canada, residing at the city of Winnipeg, in the Province of Manitoba and Dominion of Canada, have invented certain new and useful Improvements in Centering-Forms, of which the following is a specification.

My invention relates to collapsible forms for use in the construction of aqueducts, sewers, conduits and the like, and has for its objects, the provision of improved forms which may be collapsed and nested for transportation, and the provision of means whereby the forms may be erected, then collapsed and moved from point to point and reerected in accordance with the requirements of the work in progress and with a minimum amount of labor. The means by which these and other objects of the invention are attained will be found fully set out in the following specification and illustrated in the accompanying drawings in which—

Figure 1 is a view of the open end of a conduit showing my improved form with its carriage and operating means therein. Fig. 2 is an interior side view of the form and operating means, the opposite side of the form being removed and the length curtailed. Fig. 3 is an end view of a variation of the principle of the invention to form a circular conduit. Figs. 4 and 5 are details connected with the style of conduit shown in Fig. 3. Fig. 6 is a section of Fig. 2 on the line A—A. Fig. 7 is a view from above of the interlocking members of the sides of the form. Fig. 8 is a side view of the members shown in Fig. 7. Fig. 9 is a side view of the raising and lowering members showing their position when the form is collapsed. Fig. 10 is a side view of the lifting lever. Fig. 11 is a face view of the same. Fig. 12 is a side view of the cross head apart from the other features of the lifting mechanism.

Similar characters of reference indicate similar parts throughout the different views.

As shown in Fig. 1 the form is made up of sections, those indicated as B and C on the one side being connected by the hinge 2 and those on the opposite side indicated as D and E connected by the hinge 3. In Figs. 4 and 5 a further pair of sections F and G are shown, which serve to complete

the contour of the construction when a conduit circular in cross section is desired. Further reference to this style of form will be made herein later. The sections or shells may be curved as shown and they are preferably formed with the circumferentially disposed ribs 4 and 5 pertaining to the one side and similar ribs pertaining to the opposite side of which 6 is the only one in sight. The number of ribs provided is of course properly proportioned to the length of the sections and the amount of weight they will be required to sustain, and the connecting hinges 2 and 3 may be used at each rib. Lagging 7, either of wood or sheet metal, is secured to and carried by the ribs. The ribs are placed in pairs as shown and the members of each pair spaced apart. Projecting tongue members 8 (Figs. 7 and 8) are secured between the ribs 6 on the side D at the upper edge thereof and are adapted to enter the spaces between the ribs 4 and 5 on the side B to form an interlock between the sections at their meeting edges. Pins 9 and 10 pass through the inwardly projecting portions of the angles on the ribs and project on each side thereof and the tongue members 8 are bifurcated as at 11 (Fig. 8) to accommodate the pin 9 and add to the security of the interlocks in a vertical direction. Thus it will be seen that when the forms are assembled in working position that is to say with the upper edges of the sections B and D meeting each other, though intimately connected by the interlocking of the ribs, they are not permanently connected as they would be by a hinge connection and therefore may be easily separated and nested for transportation.

The style of form most generally used is that shown in Fig. 1, in which it is usual to lay the concrete floor 12 first thus providing a foundation for the longitudinal extending timbers 13 upon which the rails 14 are mounted to carry the car H. The car H extends the full length of the mold sections and carries mounted upon it the mechanism for supporting, collapsing and re-positioning the mold shells. This consists of a series of frames indicated as J and preferably three in number though but two are shown in the drawings. The frames J each comprise the four uprights 15, 16, 17, and 18 converging at the top in a shape to support the plates 19. The frames J are posi-

tioned on the car H one contiguous to each end and one intermediate the other two, so that the weight of the shell may be equally distributed over the three frames, the frames being connected each to each and braced by the longitudinally extending members 20 and the cross bars 21 and 22. It is further necessary in the placing of the frames J that each should come opposite a set of the 10 ribs 4, 5 and 6. A shaft 23 extends lengthwise of the car H and is carried in the bearings 24 at each side of the frames J. Mounted upon the shaft 23 to turn therewith and disposed within each of the frames 15 J is a curved and bifurcated lever arm 25, and immediately above each of the lever arms is a cross-head K, having a shaft 26 passing horizontally therethrough and adapted to revolve therein. The shaft 26 20 is provided on each side of the cross-heads with rollers 27 and 28 which bear upon the curved faces of the lever arms 25, and with further rollers 29 and 30 at its ends tapered to fit the V shape of the perpendicular guide members 31 at each side of the frames J in 25 which they travel. A shaft 32 projects upwardly from the center of the cross-head K and a hollow shaft 33 passes down through an opening in the plates 19 and over the 30 shaft 32 to rest in a socket 34 in the cross-head K made to receive it. The shaft 33 ends at the top in a head having a rounded portion 35 larger in diameter than the opening in the plates 19, and an upper portion 36 35 preferably shaped as shown and bifurcated to accommodate the inwardly projecting parts of the ribs 4, 5 and 6 and having horizontal grooves 37 and 38 across the top to engage the pins 9 and 10 at the upper 40 edges of the sections B and D. The cross-heads K are provided at each side with laterally extending spaced apart lugs 40 and 41 to receive between them the ends of the rods 42 and 43 which form a pivotal connection therewith. The rods 42 and 43 45 extend from the cross-heads K to the sections B and D with which they detachably connect by means of the eyes 44 at their ends which pass over the pins 45 in the sides of 50 the sections. The rods 42 and 43 have each in their length the turn-buckles 46 by which their lengths may be adjusted when found necessary. Chains 47 are shown running from the sides of the frame J to the hinges 55 2 and 3 and ending in rings 48 adapted to be hitched over the ends of the hinge pintles, the chains also having turnbuckles 49 by which their length may be adjusted. The chains are provided as a convenience while 60 preliminary adjustments are made, at which time, the width of the conduit having been determined, the length of the chains is made to correspond and they are used in the manner hereinafter described. A shaft 50 65 crosses the head frame J at the end of the

car H somewhat above the end of the shaft 23 and worm gears, 51 on the shaft 50 and 70 52 on the shaft 23, connect the two shafts. The shaft 50 is provided with a handle 53 by means of which it may be turned.

In the form under description the longitudinally extending timbers 54 and 55 (Fig. 1) form part of the lower sections C and E and partake of their movements.

To erect the form under consideration it is usual in the first instance, to raise the shells manually from each side of the car H till their upper edges meet directly over the parts 36 of the heads of the shafts 33, with the tongues 8 of the ribs 6 on the side 80 D in position between the ribs 4 and 5 on the part B. The handle 53 is then turned, the worm gears operating through the shaft 23 to swing the lever arms upwardly, thus raising the cross-heads K and the shafts 33 85 till the pins 9 and 10 are engaged in the grooves 37 and 38 on the head 36, the sections B and D being thus held in pivotal relationship to each other and supported by the upright shafts 33. The chains 47 are 90 next positioned with their rings 48 over the ends of the pintles of the hinges 2 and 3 and the sections B and D wedged out to the limit allowed by the length of the chains which is that of the conduit to be. The 95 wedging is of course temporary and accomplished by any of the well known means. The length of the rods 42 and 43 is next adjusted by means of the turnbuckles 46 so that their eyes 44 engage the pins 45 on 100 the sections B and D. The usefulness of the chains 47 ends at this point unless they be retained merely as a steady factor while the location of the forms is being changed. Also it should be mentioned that the location of the pins 45 as shown in the drawings is only relative and that they might be placed below the center of gravity 105 of the shells B and D rather than above it as shown.

It will be understood that all the levers 110 25 and cross-heads K are operated simultaneously by movement of the lever 53, and that the differential of the worm gears and the leverage of the handle 53 are calculated 115 to give a mechanical advantage equal in effect to the combined individual efforts of the numerous jack-screws with their operators previously used to effect a similar result. It will also be understood that the outer sides of the grooves 37 and 38 are perpendicular as shown in Fig. 9, and that the grooves are of ample depth to discourage any attempt on the part of the pins 9 and 10 to leave them except as the movement of the mechanism may be calculated to release them.

In a work of the nature contemplated a plurality of the forms described would be used, these being placed end to end, and the 120 125 130

self-sustaining position of each secured by the brace beams 56 and 57 which are inserted between the section timbers 54 and 55 and the track timbers 13—13, the spacing of the latter being insured by the cross ties 58.

5 An outer sheath, a fragment 59 of which is shown in Fig. 1, is spaced away from the main forms and connected therewith by the tapered bolts 60. The width of the space 10 between the sheath and the forms defines the thickness of the concrete forming the wall of the finished conduit, and when this has set the bolts are driven out and the openings grouted up.

15 As the concrete sets and it becomes desirable to move a form forward the car H is positioned below it; the shafts 33 are run up till the grooves 37 and 38 engage the pins 9 and 10; the rods 42 and 43 are connected with the pins 45 on the shells B and D; the braces 56 and 57 are removed and the lower sections C and E turned upon their hinges 2 and 3 till they occupy the positions indicated by the dotted lines C—2 in 20 Fig. 1. The lever 53 is then operated to lower the cross-heads K. As the cross-heads descend the shafts 33 descend with them till the rounded parts 35 of their heads rest upon the plates 19 when they come no 25 farther. The operation of the lever 53 is thereafter continued to effect the collapsing of the section, which is brought about by the changing angles of the rods 42 and 43, due to the vertical movement of their inner 30 ends as against the transverse movement of their outer ends. It will be noted that after movement of the shafts 33 has stopped, the upwardly projecting shafts 32 maintain the alinement of the shafts 33. When the collapsing operation is completed the car H with its load may be passed through the other forms in the series and the operation 35 described reversed to reerect the form in the new position.

40 As the work upon which forms of the present type are used are necessarily of an extensive character changes in construction to adapt the forms for different purposes do not signify, as for instance, when a circular conduit is required, it is a matter of small financial importance to provide lower 45 sections C and D without the lower timbers 54 and 55 but having tongue portions 50 (Fig. 5) adapted to enter a groove 62 at the ends of the sections F and G, (Figs. 55 3, 4 and 5) and be secured therein by the removable pins 63 and 64. In making the circular conduit the sections F and G are first positioned as shown in Fig. 4 to form 60 the inverted portion of the conduit; next they are drawn apart to allow of the track beams 13—13 being placed, when the upper sections B—C and D—E are brought into 65 action by the erecting and collapsing means previously described, the connection with the

sections F and G being made as shown in Fig. 5 when the circular form is complete as shown in Fig. 3.

From the foregoing description it will be seen that I have produced forms which may 70 easily be taken down and nested for shipment; also apparatus by means of which the forms may be accurately positioned, collapsed and reerected with a minimum of labor.

Having thus fully described my said invention what I claim is—

1. A device for the purpose described comprising a pair of top sections having 80 detachably connected interlocking means to insure the alinement of their upper edges and a second pair of sections hinged to the lower edges of the first sections, said sections, being constructed so that the mold will be self-sustaining in its expanded position and clear of obstructions to permit of the passage therethrough of a car carrying 85 a mold of similar construction; and a car and mechanism carried thereby whereby the relative positions of the upper edges of the 90 top sections to each other is maintained while the mold is lowered or raised and expanded to working position.

2. In an apparatus of the kind described, a frame work comprising a pair of curved 95 sections having ribs and pin-like projections on the sides of the ribs; a portable frame and means for supporting the frame-work from the frame, said means comprising a vertically movable member carrying an up- 100 right member engaging the projections on the ribs and lateral members connected with the vertically movable member engaging the sections of the frame-work.

3. A conduit mold comprising a pair of 105 curved sections having interengaging means at their upper edges and a second pair of sections hinged to their lower edges, stiffening ribs carried by said curved sections and 110 pin like projections on said ribs contiguous to the meeting edges of the curved sections; a car, a frame on the car and a vertically 115 movable member carried by the frame, said vertically movable member carrying an up-right member having a head shaped to receive the projections on the ribs and permit of their partial rotation, and lateral members engaging the sides of the sections of the framework.

4. An apparatus for the purpose de- 120 scribed in which is comprised a series of collapsible molds placed end to end and means for supporting, collapsing and moving the molds from one end of the series and reerecting them at the opposite end 125 thereof, said means comprising a car adapted to pass through the molds, a frame on the car, perpendicular guide members positioned at different points on the frame and cross-heads disposed to move in alinement 130

with the guides, a perpendicular member above each cross-head, lateral struts pivotally connected to the cross-heads and adapted to engage the sides of the molds, and means to simultaneously move the cross-heads vertically to lower the molds or to raise them to working position.

5. In an apparatus of the kind described, a collapsible framework comprising a pair 10 of curved sections having ribs with projections at the sides thereof and a second pair of sections hinged to the lower edge of the first sections; a portable frame and means carried by the frame to support, raise, 15 collapse and expand the framework, said means comprising a shaft, a lever-arm on the shaft and a cross-head mounted for vertical actuation by the lever-arm and carrying lateral struts to engage the sides of the 20 framework and an upright member to engage the projections on the sides of the ribs; a cross shaft, worm gears connecting the cross and first mentioned shafts and a handle whereby the cross-shaft may be rotated.
- 25 6. In an apparatus for the purpose set forth, a framework comprising a pair of curved sections, a frame and means for supporting and positioning the framework

from the frame, said means comprising a plurality of spaced apart lifting members 30 having means to engage the framework, and operative means connecting the several lifting members for simultaneous vertical movement.

7. In an apparatus of the kind described, a pair of top sections having their upper edges adapted to register with each other, a second pair of sections hinged to the lower edges of the first sections, and a third pair 35 of sections; said third pair of sections adapted to be first positioned to form the bottom of the conduit, then moved up to form the sides thereof, a frame and means for supporting the top sections from the frame and expanding said top sections to bring the lower edges of the second sections into engagement with the upper edges of the third sections, and means to form a rigid connection therebetween.

40 In testimony whereof, I affix my signature 45 in the presence of two witnesses.

HOWARD COOPER.
